UNITED STATES PATENT OFFICE.

JAMES A. BICKERDIKE, OF MILLERSVILLE, ILLINOIS.

HEN'S NEST.

No. 839,262.

Specification of Letters Patent.

Patented Dec. 25, 1906.

Application filed September 22, 1905. Serial No. 279,701.

To all whom it may concern:

Be it known that I, JAMES A. BICKERDIKE, a citizen of the United States, residing at Millersville, in the county of Christian, State 5 of Illinois, have invented certain new and useful Improvements in Hens' Nests; and I do hereby declare the following to be a full, clear, and exact description of the invention, such as will enable others skilled in the art to which it appertains to make and use the same.

This invention relates to nests for poultry.

One object of the invention is to provide a nest embodying an automatically-operated 15 door adapted to close when the fowl is in the nest to prevent entrance of other fowls thereto.

Another object of the invention resides in the provision of a nest of the character 20 stated wherein the door may be readily closed by the fowl entering the same and whereby the door may be locked automatically to prevent escape of the fowl.

A still further object is to provide a nest of 25 the character stated embodying such characteristics that the fowl may be automatically trapped and locked within the nest simultaneously, whereby it may be readily determined which fowl lays the egg.

With these and other objects in view the present invention consists in the combination and arrangement of parts, as will be hereinafter more fully described, shown in the accompanying drawings, and particularly 35 pointed out in the appended claims, it being understood that changes in the form, proportion, size, and minor details may be made within the scope of the claims without departing from the spirit or sacrificing any of 40 the advantages of the invention.

In the drawings, Figure 1 is a front elevation of my invention with the top door opened. Fig. 2 is a top plan view of the invention with the upper door in its opened position. Fig. 3 is a side view of the invention, illustrating the upper door in its closed position and the front door in its open position. Fig. 4 is a longitudinal sectional view of the structure illustrated in Fig. 3. Fig. 5 is a 50 detail view of the trigger mechanism, including its arm.

Referring now more particularly to the accompanying drawings, the present invention comprises a compartment 1, having an opening 2 in its top and an opening 3 in its front, there being a strip 4 arranged across the bot-

tom of the front opening 3 and connected in any suitable manner to the sides 5 and 6 of the compartment.

The door 7 for the front opening is hing- 60 edly mounted at its top by means of suitable eyes 8 to the rod 9, which is horizontally disposed at the upper end of the said opening 3 and secured in any suitable manner at the upper ends of the front faces of the sides 5 65 and 6 of the compartment. It will be seen that the door 7 is preferably of slatted form and that when it is closed the lower edges of the slats lie against the outer face of the aforesaid strip 4.

In order to hold the door 7 in its open position, I provide the door at its forward edge with a staple 10 for the reception of the outer end of the curved trigger-arm 11, whose inner end is provided with an eye 12 for engagement of the eye 13 of the trigger-arm support 14. As shown in the drawings, the trigger-arm support 14 is formed of a single piece of wire which is bent upon itself at its middle to form a loop 13 and spaced members 15, which diverge from the loop 13, as at 16, for a portion of their length and are thence bent around a rod 17, which is disposed at the upper rear end of the compartment 1, after which the members extend in parallel relation for the greater portion of their remaining length and have their end portions bent inwardly at right angles toward each other, as at 18. This trigger-arm support is so mounted upon the aforesaid rod 17 that it may have sliding movement longitudinally thereof.

The above-mentioned rod 17 is mounted in suitable eyebolts 18, secured upon the top faces of the aforesaid sides 5 and 6 near the rear thereof, and in order that the top opening 2 of the compartment 1 may be opened or closed, as desired, I provide an upper closure 19, which is hingedly connected in any suitable manner to the aforesaid rod 17 adjacent the supporting means 18 of the latter. It will therefore be seen that the rod 17 is disposed between the rear edge of the closure 19 and a suitable strip 20, which latter is secured in any suitable manner to the upper 105 faces of the sides 5 and 6 at the extreme rear end of the sides, and against which strip the door 19 rests in its open position. It will be seen also that the upper closure 19 extends outwardly beyond the front of the compartment to completely cover the first-named closure 7 when the latter is in its open posi- 110

tion, so that if a fowl should attempt to rest upon the nest there would not be a possibility of the first-named door 7 being accidentally closed. In other words, if a fowl should attempt to rest directly upon the front closure 7 there might be a possibility of accidental disconnection between the front closure 7 and the trigger-arm 11, whereas by constructing the upper door 19 in such manner as to project at its forward end over the front closure 7 this possibility is obviated.

Connected to the sides 5 and 6 of the compartment 1 are forwardly-directed strips 21 and 22, which are designed to prevent tilting of the nest in the event of a fowl resting upon the forward end of the upper closure 19.

When the trap is set, the upper door 19 is closed over the open front door 7 in the manner already stated to permit of the entrance of a fowl into the compartment 1. Now as the fowl enters the compartment or nest 1 it touches the trigger-arm support within the compartment, forcing the said support toward the rear wall of the compartment, and consequently causing a withdrawal of the trigger-arm 11 from engagement with the eye or staple 10 of the door 7, causing the latter to drop over the closure 3. If desired, the fowl may be taken out of the trap through the top opening 2 by opening the door 19. The weight of the door 19 is sufficient to prevent exit of the fowl through the top opening of the nest and does not require any fastening. However, there may be times when it is desired to fasten the door 7 against accidental opening. To accomplish this purpose, I provide a lock-bar whose body portion 23 is journaled through a perforation 24 in the back of the compartment or nest 1 and in the eye 25, arranged in alignment with the perforation 24, and secured in any suitable manner upon the cleat 26, secured to the front face of the side 6, there being another cleat 27, corresponding to the cleat 26, secured upon the opposite side 5 of the compartment or nest. This lock-bar has the opposite ends of its body portion bent at right angles, as indicated by the reference characters 28 and 29, the right-angularly bent portion 28 being designed to be dropped to a position diagonally across the door 7 when the said door is released, whereby the latter is locked against opening. Of course as the bent portion 28 of the locking means swings the opposite leg 29 swings correspondingly. It is obvious, therefore, that the door 7 may be locked against the outward swing when the trigger mechanism is sprung, the long arm of the locking means being arranged horizontally with the front horizontal rod upon the upper end of the door 7 falling as the front door falls and being limited in its swinging movement by means of a suitable stop 30, disposed on the back of the nest for engagement by the short end of the arm of the lock-

ing means to hold the said long leg of the locking means upon an incline across the front door 7, thereby positively locking the legs against opening. It will be observed that the body portion 23 of the locking means is arranged above the aforesaid horizontal rod and extends beneath and out of contact with the horizontal rod 17.

From the foregoing it will be understood that the fowls enter through the front opening and that they may be taken out or permitted to pass out through the upper opening of the nest. Now since the fowls are locked within the nest automatically upon their entrance thereinto it is obvious that it can be readily determined which fowl lays the egg, it being understood that the locking mechanism is actuated at the same time the front door is closed through the trigger mechanism. If desired, a series of these nests may be connected up in a horizontal line, or, if preferred, a series of nests may be arranged vertically, in which latter event the top closure 19 of the lower nest will form a support in advance of the front openings of the nest next above, and that in such an arrangement the fowls would have to be taken out or permitted to pass from the nest through the front door 7.

If at any time it is desired that the hen be not trapped when entering the nest, after the trap is set in the usual manner swing the trigger-arm support 14 forward and upward, causing the trigger-arm 11 to project through the staple 10 and causing the trigger-arm support 14 to rest against the top of compartment 1 out of reach of the hen, thus allowing the hen to pass in and out of the nest at will.

What is claimed is—

1. A trap-nest comprising a compartment having an opening in its top and an opening in its front, a door hingedly connected over the front opening, a door hingedly connected over the top opening, and a trigger mechanism depending within the compartment and having a forwardly-directed trigger-arm for co-operation with the front door to hold the latter in its open position and arranged therewith for disengagement therefrom upon movement in one direction of the trigger mechanism.

2. A trap-nest comprising a compartment having an opening in its top and an opening in its front, a door hingedly connected over the front opening, a door hingedly connected over the top opening, a trigger mechanism depending within the compartment and having a forwardly-directed trigger-arm for co-operation with the front door to hold the latter in its open position and arranged therewith for disengagement therefrom upon movement in one direction of the trigger mechanism, and means for locking the front door in its closed position.

3. A trap-nest comprising a compartment having an opening in its top and an opening in its front, a door hingedly connected with the compartment in position to close the front opening, a trigger mechanism for holding the said door in open position, and a door hingedly connected with the compartment in position to close the top opening, said door being arranged to cover the first-named door when the same is in open position.

4. A trap-nest comprising a compartment having an opening in its top and an opening in its front, a door hingedly connected with the compartment in position to close the front opening, a trigger mechanism for holding the said door in open position, and a door hingedly connected with the compartment in position to close the top opening, said door being extended beyond the front end of said

compartment to cover the first-named door 20 when the same is in open position.

5. A trap-nest comprising a compartment having an opening in its front, a door hinged to the compartment in position to close the opening, a trigger mechanism for normally 25 holding the door in open position and for actuation to release the same, and a member supported by the compartment and having a portion arranged to drop across the door when the door is dropped and to hold it in 30 closed position.

In testimony whereof I affix my signature in presence of two witnesses.

JAMES A. BICKERDIKE.
